DESIGN FOR A PICTURE FRAME

Nathaniel C. Ratner, Brooklyn, N. Y., assignor to Ranger Plastics, Inc., New York, N. Y., a corporation

Application February 22, 1944, Serial No. 112,678

Term of patent 14 years

(CL. D29—20)

To all whom it may concern:

Be it known that I, Nathaniel C. Ratner, a citizen of the United States and a resident of Brooklyn, in the county of Kings and State of New York, whose post-office address is 277 Eastern Parkway, Brooklyn, New York, have invented a new, original, and ornamental Design for a Picture Frame, of which the following is a specification, reference being had to the accompanying drawing, forming part thereof.

I claim:

The ornamental design for a picture frame, substantially as shown.

NATHANIEL C. RATNER.
